LOUIS STEINBERGER, OF BROOKLYN, NEW YORK.

DISK STRAIN-INSULATOR.

1,118,694.

Specification of Letters Patent.

Patented Nov. 24, 1914.

Application filed January 3, 1913. Serial No. 738,990.

To all whom it may concern:

Be it known that I, LOUIS STEINBERGER, residing at Brooklyn, in the county of Kings and State of New York, have invented certain new and useful Improvements in Disk Strain-Insulators, of which the following is a specification.

This invention relates to strain insulators, and particularly to those of the disk type. 10 It is a well known principle in this type of insulator, to form the surface of the disk with annular corrugations or flanges, such corrugations or flanges serving the double purpose of shedding rain water and increasing 15 the resistance to creepage around the surface of the disk from the strain member at one side of the disk to the strain member at the other side thereof by providing a greater surface-extent. 20 The object of the present invention is to provide a new and improved form of this type of insulator having all the advantages of such insulators, but having irregularities of its surface arranged so as to more effectively reinforce the structure and so as to 25 provide a continuous path from the central portion of the disk to the periphery thereof for the free passage of liquid away from the conductors at the central portion of the 30 disk.

A further object is to provide a structure as above with ridges on its opposite surfaces, and to shape the ridges on the respective surfaces so as to reinforce each 35 other for more effectively reinforcing the disk portion of the structure to the end that the disk portion may be made relatively thinner than is at present possible for given requirements.

40 A further object is to provide a structure as above, which is simple in design, which comprises a minimum of material, and which is therefore cheap to manufacture, but is nevertheless thoroughly substantial 45 and embodies maximum efficiency, both as to its insulating qualities and as to its mechanical strength, for a given sized disk.

Other objects and aims of the invention, more or less specific than those referred to 50 above, will be in part obvious and in part pointed out in the course of the following description of the elements, combinations, arrangements of parts and applications of principles, constituting the invention; and

the scope of the protection contemplated 55 will be indicated in the appended claims.

In the accompanying drawings which are to be taken as a part of this specification, and in which I have shown a merely preferred form of embodiment of the invention: Figure 1 is a top plan view of an insulator constructed in accordance with the principles of this invention; Fig. 2 is a transverse sectional view taken substantially on the plane of line 2--2 of Fig. 1; Fig. 3 65 is a view similar to Fig. 2, but illustrating a modification; and Figs. 4 and 5 are diagrammatic illustration of other modifications.

Referring to the drawings for a more detailed description of the structure illustrated, the numeral 1 indicates what may be termed the body portion of the insulator, which portion is preferably of a more or less elongated cylindrical shape adapted for receiving the strain members illustrated at 2 and 3. The strain members illustrated, each comprise a short bolt having an eye as 4 at its outer end, and having its inner end formed with a head 5 as clearly shown in Fig. 2. The inner ends of the two strain members are spaced apart and the material of the body fills the intervening space for effectively insulating the members from each other. It will be understood, that, 85 though I have shown and described the strain members as comprising simple bolts having heads spaced apart and molded within the body 1 in axial alignment, said strain members may of course take any other form 90 desired for increasing the mechanical strength of the structure in resisting strains placed upon the strain members, or for increasing the insulating value of the structure. 95

The disk portion of the structure is illustrated generally by the reference numeral 6 and comprises a wall or annular flange of substantially uniform thickness springing from the body 1 between the ends of the 100 body, preferably at the transverse median line of the body.

Formed upon the upper surface of the wall or flange forming the disk portion 6, is a ridge 7. This ridge has one end as 8 arranged near the body 1 and extends therefrom in a convolute or spiral direction about the body so that its other end as 9 lies ad-

jacent the periphery of the disk, preferably, though not necessarily, so that a line extending to it radially from the center of the body will intersect the end 8. The ridge 7 5 may be of a length for providing any number of convolutions about the body intermediate its two ends 8 and 9. The convolutions are preferably spaced apart by an even space which serves to form a groove 10 or path-way as 10 extending from the central portion of the disk in a convolute direction to the periphery of the disk and preferably entirely surrounding the body 1. Any moisture or liquid falling upon the 15 central portion of the disk, supposing the disk to have its axis substantially vertical as in Fig. 2, the liquid will flow freely along the path 10, between the convolutions of the ridge, and, when the outer flanges 15 are 20 omitted, as will be presently referred to, will fall from the outer edge of the disk. The moisture retaining pockets such as are 25 formed by the concentric ridges commonly employed are thus entirely avoided. A single convolution of the ridge 7 will provide one ridge at all points radially of the disk to act as a barrier against creepage, etc. Two convolutions of the ridge will supply two distinct ridges at all points radially of 30 the disk. The number of convolutions employed will depend upon the size of the disk and the requirements which it is designed to meet and may be altered at will within the scope of this invention.

35 It is apparent that the same object would be served if various portions of the convolutions comprised relatively straight legs as shown in the illustrations, Figs. 4 and 5, rather than the continuous, uniform, curve 40 illustrated in Fig. 1. The presence of straight legs would have the effect of further increasing the strength of the structure as has been set forth in my co-pending application, Serial No. 739,989, the legs serving 45 as straight stiff bars extending across the surface of the disk and effectually reinforcing the same. The opposite surface of the disk is provided with a ridge 11 in all respects the counterpart of the ridge 7 described upon the upper surface of the disk.

50 The ridges 7 and 11 upon the respective surfaces of the disk may be arranged directly beneath each other, if desired, but they are preferably arranged so that the 55 ridge upon one surface follows a convolute plane directly opposite to that upon the other surface, that is, supposing the ridge 7 upon the upper surface to be wound, or convoluted, in a clockwise direction away

60 from the central portion of the disk, then the ridge 11 upon the other surface of the disk would be wound, or convoluted, in a contra-clockwise direction from the central portion of the disk. By thus reversing the 65 ridges various points intermediate the

lengths thereof extend in intersecting planes and in this way lend materially greater strength to the structure.

In disks having their ridges forming poly-sided figures as in Figs. 4 and 5, the figures on the two surfaces would be preferably rotated relatively to each other, in addition to being convoluted in opposite directions. In this way relatively straight portions, or legs, of the figure on one surface 70 would intersect, or be intersected by, relatively angular portions on the other surface. The relative positions of the ridges upon the two surfaces of the disk are clearly illustrated in Fig. 1 wherein the ridges 11 75 on the under surface of the disk are shown by dotted lines, the reference numeral 12 indicating some of the points of intersection between the two ridges. Similar points are indicated by the reference numeral 13 in 80 Fig. 5.

The ridges upon the two surfaces of the disk may project outwardly from the surface of the disk for a uniform distance, that is they may be of the same height throughout their length, and the body 1 may project from the surfaces of the disk for a like distance, and also the thickness of the disk itself may be uniform throughout, if desired. It is however, apparent that these 90 various proportions may be altered within the scope of this invention, for instance as shown in the modification, Fig. 3 wherein the body 1 projects for a slight distance beyond the plane of the outer edges of the 95 ridges, and wherein the thickness of the disk is greater nearer the body and of gradually decreasing thickness toward its periphery. The difference in thickness of the disk, may be calculated so as to compensate for the difference in tendency to puncture nearer the conductors than at points farther spaced therefrom. For the same reason the height of the successive 100 convolutions of the ridges may be reduced 105 as shown in Fig. 3. The ridge may be of gradually decreasing height throughout its length from the center of the disk to the periphery and the convolutions will consequently progressively decrease in height.

110 By making the disk of greater thickness at its central portion and tapering toward its periphery, the path 10 between the convolutions of the ridge is given a continuous downward inclination toward the periphery of the disk and this inclination of course improves the value of the path as a conductor for moisture.

115 If desired an annular groove as 14 may be formed upon the periphery of the disk by 120 the addition of obliquely projective flanges 15 which will serve to effectually protect the surfaces of the disk from direct attack of rain water when the disk is disposed with its axis horizontal. Such water as strikes 125

the flanges 11 will be conducted to the lowest point and fall off without reaching either surface of the disk. The flanges 15 may, of course, be omitted if preferred so as to permit free discharge of the collected moisture, from the paths 10, over the edge of the disk.

As many changes could be made in this construction without departing from the scope of the following claims, it is intended that all matter contained in the above description, or shown in the accompanying drawings shall be interpreted as illustrative only and not in a limiting sense.

Having thus described my invention, what I claim as new and desire to secure by Letters Patent, is:—

1. In an insulator, a disk, a ridge formed upon each of the opposite surfaces of said disk encircling the central portion of the disk, and each of said ridges extending in a convolute direction from said central portion toward the periphery of the disk, the ridge upon one of the surfaces of the disk extending in a convolute direction opposite to the convolute direction of the ridge upon the other surface of the disk.

2. In an insulator, a disk having a ridge formed on each of its opposite surfaces, said ridges each extending in a convolute direction entirely surrounding the central portion of the disk, certain parts of said two ridges extending in different angular directions, and said mentioned part of one of said ridges overlying said mentioned part of the other ridge, for the purpose set forth.

3. A disk-type insulator comprising a disk of insulating material formed with a conductor attaching enlargement at its central portion, and a ridge upstanding upon one face of said disk, said ridge entirely encircling said enlargement and extending from the central portion of the disk toward the periphery thereof so as to define a moisture conducting path upon the surface of said disk encircling said enlargement and extending from the central portion of the disk toward the periphery of the disk.

4. An insulator comprising a disk of insulating material, a ridge formed upon one of the surfaces of said disk, a ridge formed upon the opposite surface of said disk, each of said ridges extending from the central portion of the disk toward the periphery thereof and one having a part overlying a part of the other, for the purpose set forth.

5. In an insulator, a disk, a ridge formed upon each of the opposite surfaces of said disk, and each of said ridges extending in a convolute direction from said central portion toward the periphery of the disk to form a plurality of convolutions about said central portion, each of said ridges comprising a plurality of substantially straight legs connected end to end in angular relation, and portions of some of the straight

legs of the ridge upon one surface of said disk overlying portions of some of the straight legs upon the other surface of said disk, and said overlying portions extending in different angular directions.

70

6. A disk-type insulator comprising a disk of insulating material, a ridge formed upon one of the surfaces of said disk, a conductor attaching part carried by said disk, said ridge extending in a convolute direction to form a plurality of successive convolutions upon the surface of said disk, encircling said conductor attaching part, and said ridge being of gradually decreasing height substantially throughout its length so that the convolutions thereof are of successively decreasing height.

7. A disk-type insulator comprising a disk of insulating material, and a ridge extending in a curved direction entirely surrounding a portion of the surface of the disk and having its opposite ends spaced apart upon the surface of the disk.

8. A disk-type insulator comprising a disk of insulating material, a ridge formed upon one surface of said disk, a ridge formed upon the opposite surface of said disk, each of said ridges extending in a curved direction longitudinally of its length, and one having a part overlying a part of the other, for the purpose set forth.

9. A disk-type insulator comprising a disk of insulating material, and ridge formed upon one of the surfaces of said disk, a ridge formed upon the opposite surface of said disk, each of said ridges extending from the central portion of the disk toward the periphery thereof for a plurality of convolutions about said central portion of the disk, and one of said ridges having parts overlying parts of the other ridge at a plurality of spaced points in its length.

10. A disk-type insulator comprising a disk of insulating material, and a ridge upstanding upon one surface of the disk entirely surrounding a portion of said surface and lapping upon itself in spaced relation to provide a plurality of barriers upon said surface radially from said surrounded portion and at the same time to provide a moisture conducting path from said surrounded portion between said barriers.

11. A disk-type insulator, comprising a disk of insulating material, and a ridge upstanding upon one surface of the disk entirely surrounding a portion of said surface and lapping upon itself in spaced relation to provide a plurality of barriers upon said surface radially from said surrounded portion.

12. A disk-type insulator, comprising a disk of insulating material, and a ridge upstanding upon one surface of the disk entirely surrounding a portion of said surface and being arranged to define a moisture con-

125

130

ducting path upon said surface extending away from said surrounded portion.

13. A disk-type insulator, comprising a disk of insulating material formed with a conductor attaching part thereon, and a ridge upstanding upon one surface of said disk having parts disposed to provide a plurality of spaced barriers upon said surface in a radial direction from said conductor attaching part.

14. A disk-type strain insulator, comprising suspension members, a mass of insulating material partially enveloping the same and having a disk portion, said disk portion being provided upon one of its surfaces with a ridge upstanding therefrom surrounding one of said suspension members and extending in a convolute direction toward the periphery of the disk portion.

15. A disk-type strain insulator, comprising suspension members, a mass of insulating material partially enveloping the same and having a disk portion, said disk portion being provided upon one of its surfaces with a ridge upstanding therefrom surrounding one of said suspension members

and extending in a convolute direction toward the periphery of the disk portion, and an annular flange formed upon each surface of the disk portion to form an annular moisture conducting path at the periphery of said disk portion.

16. A disk-type insulator, comprising a disk of insulating material formed with a conductor attaching part thereon, a ridge upstanding upon one surface of said disk having parts disposed to provide a plurality of spaced barriers upon said surface in a radial direction from said conductor attaching part, in combination with means at the periphery of the disk forming a moisture conducting path about the periphery of the disk, said means comprising in part an annular flange upstanding upon the mentioned surface of said disk arranged to protect said ridge.

In testimony whereof I affix my signature in the presence of two witnesses.

LOUIS STEINBERGER.
